Application March 3, 1951, Serial No. 213,765

15 Claims. (Cl. 240—8.16)

1

This invention relates to lamps and more particularly to a lamp adapted to be mounted on a wall with special reference to wall panels of vehicles such as aircraft, trains, buses, and the like.

Since the invention has special advantage for use in aircraft and is being initially incorporated in a structure for that purpose, the description of such a panel light is selected for the present disclosure. Those skilled in the art will find in this embodiment adequate guidance for applying the underlying principles of the invention to other specific purposes wherever the invention may have utility.

The present preferred form of the invention arises from a combination of requirements peculiar to aircraft.

Panel lights are mounted in wall openings to direct light beams in various directions relative to the walls for various illumination purposes. It is highly desirable, for a number of reasons, to provide a single model of such a lamp that may be easily and quickly set when installed to direct its light beam in any desired direction. The present invention meets this need with a novel arrangement in which the lamp housing is supported by a ball member that is universally adjustable in a complementary ball socket.

A special feature of the invention is provision for directing the light beam at an exceptionally low angle relative to the wall. For this purpose the socket for the ball member is in effect tilted or inclined to make such a low angle possible in one radial direction and the socket is rotatable to vary this direction as may be desired in installing the lamp or in subsequently adjusting the lamp.

While the normal friction of the ball member in the socket may be relied upon to hold the lamp in any desired angle of adjustment, special clamping means may be employed for this purpose. The preferred form of the invention is characterized by an adjustment that not only releasably tightens the socket to clamp the ball member at a selected position, but also and at the same time releasably clamps the socket itself in a selected radial direction of tilt.

Because space considerations are important in aircraft and especially because a projecting lamp structure is a hazard, it is desirable to have most of the lamp structure set back from the front face of the wall and, of course, all wiring connections are behind the walls in aircraft construction. This situation poses certain problems in servicing and inspecting the lamp, especially in the replacement of bulbs in the concealed lamp structure.

2

The present invention meets this problem by making the supporting structure for the lamp releasably attachable to the wall in a manner to permit removal of the lamp from the wall with a single hand movement. The arrangement is such that this removal of the lamp structure not only exposes the wiring for the lamp, but also makes the lamp structure, including the bulb socket, accessible for inspection and servicing.

10 No tools whatsoever are required to carry out this procedure and replace a burnt out light bulb. An important feature is that removal of the lamp structure in this manner does not disturb the setting of the lamp with respect to the direction and angle at which the lamp is adjusted at the time of installation.

A further requirement common in aircraft usage, especially in military planes, is provision for darkening the light beam from the lamp when desired. Thus red filters are commonly used on the lamps to avoid interfering with the vision of personnel at night and to keep the illumination from making the aircraft conspicuous. It is undesirable to use filter accessories that are separate from the lamp structure and may be lost. In this regard the invention has the advantage of a novel form of built-in adjustable filter which may be moved into and out of effective position by a simple finger adjustment. Any necessity for adding special external controls for the filter is avoided by making the exposed front end of the lamp housing rotatable with the filter operatively responsive to such rotation.

35 The various features and advantages of the invention will be apparent from the following detailed description taken with the accompanying drawings.

In the drawings, which are to be regarded as merely illustrative,

40 Figure 1 is a front elevation of the invention as mounted in an aircraft wall;

Figure 2 is a rear elevation of the invention with a portion of the lamp housing broken away;

45 Figure 3 is a side elevation of the lamp proper with associated supporting structure shown in section;

Figure 4 is a sectional view taken as indicated by the line 4—4 of Figure 3; and

50 Figure 5 is a perspective view of the filter and an associated control member, the two parts being shown spaced apart for clarity.

The drawings show the invention mounted in a circular opening in a thin sheet metal wall 10 that is typical of aircraft construction. The general arrangement consists essentially of: support structure, generally designated 11, that is adapted

for mounting in the wall opening and forms a spherically curved socket 12; a ball member 13 that seats in the socket 12 and is hollow to form a passage for the light beam from the lamp; a lamp housing, generally designated 14, mounted on the ball member to extend rearwardly therefrom; and a filter element 15 that is manually adjustable between an edgewise position shown in solid lines in Figure 4 and a transverse position shown in dash-dot lines.

While the support structure 11 may take various forms and may be quite simple in construction, the present preferred embodiment of the invention is characterized by a tilted socket 12 that is rotatably adjustable with respect to the wall opening and is also adjustable to clamp the ball member 13 in any desired position. To provide these features it is advantageous to use a support structure 11 that includes a front plate 18, a back plate 19, and an outer ring 20. Since the sheet metal wall 10 is thin and somewhat flexible, an annular mounting element herein shown as a flanged collar 23 is mounted on the inner side of the wall around the rim of the circular wall opening for the dual purpose of locally reinforcing the wall and of cooperating with the ring 20 to mount the support structure 11 in place in a conveniently releasable manner.

In the construction shown the flanged collar 23 is attached to the wall 10 by suitable rivets 24 and for the purpose of cooperating with the ring 20, is provided with two fixed pins 25 that extend radially into the wall opening from diametrically opposite sides of the collar. For cooperation with the pins 25 the ring 20 has a suitable pair of spring clips 26 mounted thereon by rivets 27, the spring clips having upturned ends 28 to slide over the pins and being formed with offset portions 29 to releasably grasp the pins. It may be noted that the spring clips 26 are oppositely disposed for movement into engagement with the pins 25 by counter-clockwise rotation of the ring as viewed from the rear in Figure 2, or clockwise rotation as viewed from the front.

Preferably the arrangement is such that when the lamp is mounted in the wall the spring clips 26 exert pressure in cooperation with the front plate 18 to hold the support structure 11 snugly in place with no looseness. For this purpose the front plate 18 has the configuration of a shallow cup to fit back into the wall opening and is formed with a radial rim flange 30 that is normally pressed against the front face of the wall 10 by the spring action of the two clips 26.

The socket 12 is formed by the two plates 18 and 19 in cooperation with each other and has an inner configuration which may be defined as conforming to a sphere truncated from two sides, for example, by parallel planes lying equidistant on opposite sides of the center of the sphere. In Figures 3 and 4 the edges of the two opposite socket openings are indicated by dot-dash lines 33 which represent the intersection of the hypothetical planes with the hypothetical sphere and it will be noted in Figure 4 that these two parallel planes are inclined or tilted with respect to the planes of the front and back plates 18 and 19. To provide this tilted socket the front plate 18 is formed with a forwardly presented lip or rim 34 and the back plate 19 is formed with a similarly rearwardly presented lip or rim 35, each lip tapering in both directions from a high point 36 and the two high points being at diametrically opposite positions.

The front and back plates 18 and 19 cooperate to releasably clamp the ring 20 from opposite sides and for the purpose of centering the two plates relative to the ring 20, the back plate 19 is cut away at its inner margin to provide a shallow annular seat 38 for the ring. Suitable means to draw the two plates 18 and 19 together for clamping the ring 20 may comprise a pair of screws 40 that extend through the two plates from the front and thread into nuts (not shown) encased in sheet metal jackets 41. Each of the jackets 41, which is of well known construction, has a pair of wings attached to the back plate 19 by rivets 43.

The ball member 13, which is of the same general truncated spherical configuration as the socket 12, is adapted in any suitable manner to carry the lamp proper together with the adjustable filter element 15. In the construction shown the lamp housing 14 is of cylindrical configuration with a rear end wall 45 and is held in assembly with the ball member 13 by a split expansile ring 46. Preferably the end wall 45 is dished as shown and is polished on its inner surface to serve as a light reflector.

Integral with the lamp housing 14 is a radially positioned collar 47 that is united with the cylindrical body of the lamp housing by a conical skirt 48 and is adapted to hold a socket assembly, generally designated 50, in which is mounted a lamp bulb 51. The outer end of the socket assembly 50 has suitable terminals 52 for electric wires (not shown) and is provided with a radial flange 53 for releasable engagement by a rubber cup 54 on the end of a rubber tube 55 that protects the wires. The rubber cup 54, which is reinforced by a rim bead 56, may be peeled away from the flange 53 for access to the wires whenever required.

For convenience in replacing the lamp bulb 51 whenever necessary, the housing 14 has a suitable opening 60 in its circumferential wall which is large enough to pass the lamp bulb and is positioned for easy access to the bulb. Normally the opening 60 is closed by a split, thin-walled sleeve 61 that is resiliently contractile to releasably embrace the lamp housing 14 and may be quickly removed and replaced as desired without the use of tools.

Since it is contemplated that the lamp will project a relatively narrow beam of light it is desirable to include a lens 62 in the form of a condenser. In the construction shown the interior of the lamp housing 14 is cut away at its forward end to provide an annular shoulder 64 against which the lens 62 abuts and the lens is held in place by a suitable flanged retaining sleeve 65 that is mounted in the lamp housing 14 with a forced fit.

As heretofore stated, the filter element 15, which is a flat lens or disc of red glass, is responsive to rotation of a tubular extension of the lamp housing. Figure 4 shows a knurled tubular member 67 rotatably mounted in the forward portion of the ball member 13, the tubular member being rotatably held in place by a radial shoulder 68 in abutment with a complementary annular shoulder 69 formed in the ball member 13.

The filter element 15 is pivotally mounted inside the tubular member 67 by suitable pivot pins 70 that provide a pivot axis diametrically positioned to intersect the longitudinal axis of the tubular member. Adjacent the inner end of the tubular member 67 is a guide, generally des-

ignated 11, having two spaced walls 12 forming a fixed radial guideway 13. As best shown in Figure 5, the guide 11 may be in the form of a ring having two fingers to serve as the walls 12 of the radial guideway 13. Such a ring may be maintained against rotation in the ball member by forced fit or other provision.

A suitable fixed extension from the filter element 15 cooperates with the radial guideway 13 to rotate the filter element in response to rotation of the tubular member 67. In the construction shown, a simple pin 75 is fixedly mounted in the filter element 15 to serve as an operating arm for sliding engagement with the radial guideway 13. To provide the required coaction, the axis of the pin 75 should pass through the point at which the diametrical pivot axis of the filter element intersects the longitudinal axis of the tubular member 67. The pin should be approximately at a 45 degree angle relative to the plane of the filter element 15 and should likewise be in a plane approximately 45 degrees inclined from the axis of the two pivot pins 70. With the radial guideway 13 also inclined approximately 45 degrees from the pivot axis, as shown in Figures 1 and 5, rotation of the tubular member 67 causes rotation of the filter element 15 arising from sliding confinement of the end of the pin 75 in the guideway 13.

It is to be noted that the radial guideway 13 holds the pin 75 against any movement except angular movement in the plane defined by the guideway and the longitudinal axis of the tubular member 67. Rotation of the knurled tubular member 67 presses the free end of the pin 75 against one wall of the fixed radial guideway 13 and thereby sets up reaction forces that rotate the filter element about its axis. Thus the filter element not only rotates about the axis of the two pivot pins 70, but also simultaneously rotates about the axis of the pin 75. It will be noted in Figure 4 that one of the walls 12 of the radial guideway 13 serves as a stop to limit the rotation of the filter element 15 at the edgewise position of the filter element.

In the course of rotation of the filter element between the edgewise position shown in solid lines in Figure 4 and the transverse position shown in dash-dot lines in Figure 4 as well as in full lines in Figure 1, the pin first moves inward from the outer end of the radial guideway 13 and then returns to the outer end of the guideway. The arrangement may be such, therefore, that the pin cooperates with the outer end of the radial guideway to serve as a stop at the transverse position of the filter element.

Operation of the invention may be readily understood from the foregoing description. With the screws 40 tightened to cause the two plates 18 and 19 to grip the ring 20, it is a simple matter to mount the support structure 11 in the wall opening after the electrical connections to the lamp have been completed through the rubber tube 55. The assembly is simply moved in to the wall opening and then rotated clockwise to bring the two spring clips 26 into retaining engagement with the fixed pins 25.

Once the ring 20 has been engaged with the pins 25 in this manner, the two screws 40 may be loosened sufficiently to permit the two plates 18 and 19 to be rotated about the ring to cause the socket 12 to tilt in any direction desired. In any installation where it is desirable to have the lamp housing 14 directed at an angle as close as possible to the plane of the wall 10, the two plates

18 and 19 will be rotated accordingly to tilt the socket 12 in the desired direction.

When the two plates 18 and 19 have been rotated for this purpose the projecting tubular member 67 is used in the manner of a handle to rotate the ball member 13 in the socket 12 as may be required to position the lamp housing 14 at the desired angle in the desired direction and then the two screws 40 are tightened to clamp and fix the assembly at the desired adjustment setting. The tightening of the two screws 40 not only causes the two plates 18 and 19 to grip the ring 20 in a rigid manner, but also draws the two lips 34 and 35 against the ball member 13 with sufficient pressure to clamp or freeze the ball member in the socket 12.

When the lamp is in use, it is a simple matter to rotate the tubular member 67 manually to place the filter element 15 in either of its two limit positions. If the lamp bulb 51 burns out, it is a simple matter to release the assembly from the wall opening by a twist of the wrist to disengage the spring clips 26 from the fixed pins 25. No tools are required to remove the thin-walled sleeve 61 for access to the burnt out bulb.

It is especially noteworthy that such removal of the assembly from the wall opening does not require loosening of the two screws 40 and, therefore, does not disturb the original setting and adjustment of the parts that were fixed at the time of installation by tightening the two screws. Thus removing the lamp from the wall for service or inspection does not require any adjustment whatsoever in replacing the assembly.

Although the now preferred embodiment of the present invention has been shown and described in detail herein, it is to be understood that the invention is not to be limited by this disclosure, for it is susceptible to changes in form and detail within the scope of the appended claims.

Having described my invention, I claim:

1. A lamp of the character described comprising: a lamp housing having an opening for directing a light beam therefrom; a tube positioned to serve as an extension of said opening, said tube being mounted on said housing for rotation about its longitudinal axis; a filter pivotally mounted inside said tube for rotation about an axis extending diametrically of the tube; a guide spaced from said filter in line with said opening, said guide having a fixed guide channel positioned radially of the tube at an acute angle to the plane defined by the longitudinal axis of the tube and said pivot axis of the filter; and an operating member fixedly carried by said filter in sliding engagement with said guide channel to cause rotation of the filter on its pivot axis in response to rotation of said tube on its longitudinal axis.

2. A lamp as set forth in claim 1 in which said operating member is a pin mounted on the filter at an acute angle thereto in alignment with the intersection of the pivot axis of the filter with the longitudinal axis of the tube.

3. A lamp of the character described for mounting in an opening, said lamp comprising: a support structure adapted for mounting in said opening, said structure providing a socket having the inner configuration of a sphere truncated by substantially parallel planes on opposite sides of the center of the sphere; a truncated ball member movably embraced by said socket, said ball member having a passage therethrough; a lamp housing carried by said ball member with an

opening for directing a light beam through said passage; a tube positioned forward of said opening in line with the opening, said tube being supported by said ball member and being rotatable about the longitudinal axis of the tube; a filter member pivotally mounted inside said tube for rotation about an axis extending diametrically of the tube; a guide spaced from said filter member in line with said opening, said guide having a fixed guide channel positioned radially of the tube at an acute angle to the plane defined by the longitudinal axis of the tube and said pivot axis of the filter element; and an operating arm fixedly carried by said filter element in sliding engagement with said guide channel to cause rotation of the filter element on its pivot axis in response to rotation of said tube on its longitudinal axis.

4. A lamp as set forth in claim 3 in which said lamp housing is mounted in the rear end of said passage in the ball member and said tube is mounted in the front end of the passage.

5. A lamp of the character described for mounting in an opening in a wall, said lamp comprising: support structure adapted for releasable attachment to the wall to close said opening, said structure forming a central truncated ball socket; a ball member seated in said socket, said ball member having a passage therethrough; a lamp housing mounted on the back of said ball member to direct a beam of light through said passage; a tubular extension rotatably mounted at the front of said ball passage; and a filter element movable between a position across the axis of said passage and a position edgewise to the passage; and means to move said filter between said positions in response to rotation of said tubular extension.

6. A lamp of the character described for mounting in an opening in a wall, said lamp comprising: a ring member for said wall opening; means to releasably attach said ring member to the wall at the wall opening; two plates lying against opposite sides of said ring, said plates having apertures with lips cooperating to form a ball socket; a ball member seated in said socket, said ball member having a passage therethrough; means to releasably draw said two plates towards each other to clamp the plates to said ring; a lamp housing mounted on the back of said ball member to direct a beam of light through said passage; and a tubular extension rotatably mounted at the front of said ball passage; and a filter movable between a position across the axis of said passage and a position edgewise to the passage; and means to move said filter between said positions in response to rotation of said tubular extension.

7. A lamp as set forth in claim 6 in which said drawing means releasably contracts said socket around said ball member to fix the position of the ball member in the socket.

8. A lamp of the character described for mounting in an opening in a wall, said lamp comprising: an annular mounting element to be fixed to said wall and including means concentric with the opening of said wall, two plates positioned face to face for spanning said annular mounting element, each of said plates having an aperture with a lip at one peripheral portion of the aperture, the lip on each plate being turned outward in the direction away from the other plate, said lips cooperating to form a socket open on two sides of the plates; a ball member having a passage therethrough seated in said socket; a lamp hous-

ing mounted on said ball member at the rear thereof and projecting light through said passage, said lips being at diametrically opposite positions relative to said apertures whereby said socket may be tilted relative to the plane of said opening so that the lamp on said ball member may be turned to relatively low angles relative to said wall; means to interconnect said two plates to hold the plates and ball member in assembled positions; and means for releasably mounting said assembled plates and ball member to the means of said mounting element concentric with said opening.

9. A lamp of the character described for mounting in an opening in a wall, comprising: an annular mounting element to be fixed to said wall concentric with said opening; a support structure adapted for mounting across the opening of said mounting element, said structure providing a socket having an inner configuration conforming to a sphere truncated on two sides; a ball member having a passage therethrough seated in said socket and projecting outwardly of the truncated open sides; a lamp housing carried by the inner portion of said ball member for directing a light beam through said passage, the forward truncated side of said socket being inclined to extend forwardly relative to said support structure to permit rotation of said lamp housing to a relatively low angle with reference to the wall; and means for releasably connecting said support structure to said annular mounting element whereby said support structure may be detached from the latter to expose said lamp housing for service and maintenance.

10. A lamp assembly of the type described to be mounted behind a wall having an opening therethrough, comprising: an annular mounting element to be fixed to said wall concentric with said opening; a support member; means carried by said mounting element and cooperatively engageable with means carried by said support member for releasably connecting said support member to said mounting element; means carried by said support member forming a socket open on two sides thereof; a ball member having a passage therethrough seated in said socket; and a lamp housing carried by said ball on the inner side thereof for directing light forwardly through said passage; said support member including means for clamping said socket about said ball after the latter has been moved to a desired position of adjustment for holding said ball and associated lamp socket against movement, said support member being detachable from said mounting element whereby said lamp housing may be withdrawn for service and maintenance without affecting the relative position of the ball within said socket.

11. A lamp of the character described for mounting in an opening in a wall, comprising: an annular mounting element to be fixed to the wall concentric with said opening; a ring member; means partially carried by said ring member and partially carried by said support member for detachably mounting said ring member in a pre-selected position concentrically within the opening of said support member; a ball-receiving socket open at opposite ends; means for rotatably mounting said socket to said ring member; a ball member having a passage therethrough seated in said socket; a lamp housing mounted to the rear portion of said ball member for projecting light rays forwardly through said passage; releasable means for holding said socket mounting means

against rotation relative to said ring, whereby said socket may be moved to and held in a pre-selected position relative to said ring; the means detachably mounting said ring member to said mounting element permitting said lamp housing to be demounted from the opening in said wall for service and maintenance and remounted without affecting the angular adjustment of said socket relative to said ring.

12. A lamp assembly to be mounted behind a wall having an opening therethrough comprising: an annular support member to be fixed to said wall concentric with said opening; a ring member; means partially carried by said support member and partially carried by said ring member for detachably mounting said ring member within said wall opening; two plates lying against opposite faces of said ring member, said plates having apertures with defining rim elements cooperating to form a ball-receiving socket having an axis askew to the faces of said plates engaged with the ring member; a ball member having a passage therethrough seated in said socket, said plates being rotatable relative to said ring member to vary the angular direction of the axis of said socket relative to said ring member; manually releasable means for drawing said plates toward each other to clampingly engage said ring therebetween whereby said plates may be held against rotation relative to said ring and the ball against movement relative to said socket; and a lamp housing mounted to the inner end of said ball member for directing light forwardly through said passage.

13. A lamp assembly to be mounted behind a wall having an opening therethrough, comprising: a ring member; a pair of plates arranged on opposite sides of said ring member, said plates having apertures with defining rim elements cooperating to form a ball-receiving socket; a ball member having a passage therethrough seated in said socket; a lamp housing; means for securing said housing to said ball member to project rearwardly therefrom and directing a light beam forwardly through said passage; means for clampingly engaging said ring intermediate said plates with said socket clampingly retaining said ball against accidental movement from a desired adjusted position relative to said socket; an annular element to be secured to the rear face of said wall concentric with the opening therein; a collar carried by said element and projecting rearwardly of said wall; and releasable means for concentrically mounting said ring within said collar with the plates closing the opening of said collar and mounting said ball and associated lamp housing behind said wall.

14. A lamp assembly of the type described, comprising: a first ring, adapted to be mounted to the rear face of a wall having an opening therein, said first ring having an annular flange concentric with said opening; a pair of diametrically

- opposed pins radially extending inwardly from said flange; a second ring; a pair of resilient fingers diametrically carried by said second ring and adapted to be detachably engaged over said pins by relative rotational movement of said two rings; a pair of plates arranged on opposite sides of said second ring, said plates having apertures with rims cooperating to form a ball socket; a ball member having a passage therethrough seated in said socket; a lamp housing carried by the rear portion of said ball member and directing a light beam forwardly through said passage; and means for clampingly engaging said plates against opposing faces of said second ring to mount said ball and lamp housing thereto and to close the opening of said second ring, said second ring being removable from said first ring by disengaging said fingers from said pins, whereby said lamp housing may be withdrawn for service and maintenance.
15. A lamp assembly of the type described, comprising: an annular mounting element to be fixed to the rear surface of a wall having an opening therein; an annular flange carried by said element extending rearwardly of said wall concentric with said opening; a ring; means extending inwardly from said flange and engageable with means carried by said ring for detachably mounting the latter within the opening of said annular element; a pair of plates arranged on opposite sides of said ring, said plates having apertures with defining rim elements cooperating to form a ball-receiving socket; a ball member having a passage therethrough seated in said socket; a lamp housing carried by said ball member at the rear thereof and directing light forwardly through said passage; and means for clampingly engaging said plates against opposing faces of said ring with the rim elements of said plates retaining said ball against accidental movement from a desired adjusted position relative to said socket, said ring being removable from said mounting element by disengaging said means of the flange from the means of the ring, whereby said lamp housing may be withdrawn for service and maintenance and remounted without affecting the relative position of the ball within said socket.
